[57] **CLAIM**

The ornamental design for a horizontal variable speed turbine pump, as shown.

DESCRIPTION

FIG. 1 is a front elevational view of a horizontal variable speed turbine pump showing our new design;
FIG. 2 is a rear elevational view thereof;
FIG. 3 is a top plan view thereof;
FIG. 4 is a bottom plan view thereof;
FIG. 5 is an enlarged left side elevational view thereof;
and,
FIG. 6 is an enlarged right side elevational view thereof.

Fig. 3.

Fig. 4.

FIG. 6

FIG. 5
